UNITED STATES PATENT OFFICE.

JOHN W. HALTERMAN, OF WILLOWS, CALIFORNIA.

MECHANICAL RAZOR.

1,286,606.

Specification of Letters Patent. Patented Dec. 3, 1918.

Application filed March 2, 1917. Serial No. 151,899.

To all whom it may concern:

Be it known that I, JOHN W. HALTERMAN, a citizen of the United States, residing at Willows, in the county of Glenn, State of California, have invented certain new and useful Improvements in Mechanical Razors; and I do declare the following to be a full, clear, and exact description of the same, reference being had to the accompanying drawings, and to the characters of reference marked thereon, which form a part of this application.

This invention relates to improvements in mechanical razors designed for use in shaving the hairs of the face by mechanical means rather than the now commonly used manually operated razors of various types.

I am aware that mechanical razors have heretofore been invented and I am somewhat familiar with the prior art and the aim of my present invention is to overcome some of the deficiencies disclosed by such prior art and one of the most important of these is the guard means used to prevent the skin or flesh of the face from being drawn or rolled between the stationary blade and the movable blade. As far as I know all previous guards for this purpose have been formed directly on the surface of or on the outside of the casing. Such a structure as this is rougher on the face and rides some of the hairs down while passing over the face instead of cutting them. Also the guard on the outside is a hindrance to close shaving.

I have therefore devised a means or structure whereby the guards are placed within the casing and operable preferably with or as a part of the movable blade. This movement will be either rotary or oscillating and in the present disclosed type, which is the one I give preference to at this time, I have shown an oscillating cutter with the guards connected therewith inside of the casing and movable as a unit with such cutter. I have further provided a specially designed mechanism for operating such oscillating cutter.

A still further object of the invention is to provide an easily removable supporting handle for the cutter so that the same can be readily taken apart for the purpose of cleaning the razor and this removable handle member is also connected onto the razor casing in such a manner as to maintain the same relative position with respect to the oscillating cutter for a purpose as will presently appear.

A further object of the invention is to produce a simple and inexpensive device and yet one which will be exceedingly effective for the purposes for which it is designed. 60

These objects I accomplish by means of such structure and relative arrangement of parts as will fully appear by a perusal of the following specification and claims.

In the drawings similar characters of reference indicate corresponding parts in the several views.

Figure 1 is a perspective view of the complete device.

Fig. 2 is a vertical transverse section 70 through the center of the razor.

Fig. 3 is a vertical longitudinal section through the entire device.

Fig. 4 is an end view of the razor casing showing the handle removed. 75

Fig. 5 is the bottom plan view of the razor casing.

Referring now more particularly to the characters of reference on the drawings, I first provide a razor casing 1 which is substantially cylindrical in cross section and provide it for a portion of its length with a small longitudinal slot 2, the edges of such slot being sharpened down to form stationary cutting blades. 80

In each end of the casing 1, I provide an adjustable bearing member 3 substantially as shown in my pending application for patent filed November 2nd, 1916, Serial Number 129,105. 90

Journalized in the bearing members 3, I provide a shaft 4.

Secured to or formed as a component part of this shaft 4 are a plurality of spaced segmental guard members 5 projecting to a point closely adjacent the slot 2 and arranged to oscillate back and forth across said slot with a rocking motion of the shaft 4 imparted thereto in a manner as will presently appear. A small cutter bar 6 is rigidly set into the outer edge of the guards 5 or formed as a component part of said guards. This bar 5 has a slight angling position with respect to the cutting edges of the slot 2. In practice the lower edge of the bar 6 projects below the lower edges of the guards 5 a distance equal to the approximate diameter of a hair. 100

Fixed centrally of the length of the shaft 4 is an upwardly projecting arm 7, its upper end being bifurcated as at 8 to receive a small driving wheel 9. This driving wheel

9 is secured in an eccentric manner to the driving shaft 10 suitably journaled in side walls of the spring clip member 11. The sides of the member 11 are slightly resilient 5 and provided with slots 12 adapted to fit over the side set screw 13 of bearing members 3. By means of this structure the position of the member 11 relative to the shaft 4, is always the same so as to make positive 10 the connection between the members 9 and 8. The necessity of this will be clearly apparent since it will be noted that the bars 3 may be adjusted to different positions and if the member 11 in which the shaft 10 is 15 journaled, is not relatively adjusted, the connection between the members 8 and 9 might become too loose or too tight as the case might be. On the member 11 is fixed the handle member 14 within which is a flexible 20 cable suitably connected to the driving shaft 10. The cable 15 may be driven by any motive means found desirable.

When motion is imparted to the shaft 10, the rotation of such shaft rotates the driving wheel 9 with an eccentric motion which imparts to the member 7 an oscillating motion. This in turn imparts to the shaft 4, guards 5 and cutter bar 6 a similar oscillating motion. With this action the bar 6 30 moves back and forth across the slot 2. The casing 1 being placed against the face causes the hairs on the face to project into the slot 2 where they are engaged by the bars 6 and carried into contact with the cutting edge 35 along the slot 2 where they are cut off with a shearing action due to the fact that the bar 6 is slightly angled with respect to the cutting edge as previously described. The guards 5 hold the skin and flesh of the face 40 from being rolled in between the cutter bar and the cutter edge. The small distance that the bar 6 projects below the guards is not enough to allow of the flesh or the skin being rolled between such bar and the cutting edge 45 but at the same time it allows of a continuous cutting surface uninterrupted by the guards. If the guards came immediately adjacent the cutting edge it might be possible that a hair would get caught between the guard and the cutting edge with 50 the result that it would be pulled instead of cut. It is for this reason that the bar 6 projects below the guards 5 a distance equal to the diameter of a hair so that all the hairs 55 which are drawn into the casing will be sheared off with no possible chance of them being caught and pulled.

While of course it would be possible to construct the cutter bar 6 so that it would 60 perform a complete rotary motion instead of an oscillating motion, still I believe the

oscillating motion to be preferable for the reason that the hairs are cut against either edge of the slot 2. Thus no matter which way the hairs on the face lie, they will be 65 picked up and cut whereas if the cutter rotated only, the razor would have to be positioned so as to work against the hairs in order to be efficient in its action. By the construction here shown however they will be 70 quickly cut off irrespective of which way they lie since if the cutter rides over them when moving in one direction it will pick them up and cut them off when moving in the reverse direction. 75

The top of the casing 1 is provided with a free open portion 1^a so as to allow of a free movement of the wheel 9 and also to allow of the razor being readily cleaned when the spring clip member 11 is removed from the 80 screws 13.

From the foregoing description it will be readily seen that I have produced such a device as substantially fulfills the object of the invention as set forth herein. 85

While this specification sets forth in detail the present and preferred construction of the device, still in practice such deviations from such detail may be resorted to as do not form a departure from the spirit 90 of the invention, as defined by the appended claims. 95

Having thus described my invention what I claim as new and useful and desire to secure by Letters Patent is:

1. A mechanical razor comprising a casing provided with a slot having its edges formed into cutting blades, a longitudinal driven shaft journaled in the casing, a plurality of guards fixed to the shaft transversely of the slot area, a cutting blade set into the guards and coacting with the cutting blades and projecting beyond the outer edge of the guards for a distance substantially equal to the diameter of a hair whereby a continuous cutting area will be provided along the entire length of the cutting blades to prevent any hair being caught and pulled between the guards and the slot blades while at the same time the space between the casing and guards will be so small as to prevent the flesh of the operator from being drawn into the casing and cut. 100 105 110 115

2. A mechanical razor comprising a casing provided with a slot having its edges formed into cutting blades, a plurality of spaced guard plates within the casing having an oscillating movement transversely across the slot area, and a cutter bar carried by the guards and coacting with said blades. 120

In testimony whereof I affix my signature.

JOHN W. HALTERMAN.
